UNITED STATES PATENT OFFICE

146,759

DESIGN FOR A DISPOSABLE RAZOR

Albert D. Brown, Atlanta, Ga.

Application December 7, 1945, Serial No. 124,462

Term of patent 14 years

(Cl. D22—3)

To all whom it may concern:

Be it known that I, Albert D. Brown, a citizen of the United States, residing at Atlanta, in the county of Fulton and State of Georgia, have invented a new, original, and ornamental Design for a Disposable Razor, of which the following is a specification, reference being had to the accompanying drawing, forming part thereof.

Figures 1 and 2 are perspective views of opposite faces of a disposable razor, showing my new design.

I claim:

The ornamental design for a disposable razor, as shown.

ALBERT D. BROWN.
